[57] **CLAIM**

The ornamental design for a watch, as shown and described.

DESCRIPTION

FIG. 1 is a top, front and right side perspective view of a watch showing my new design;

FIG. 2 is a bottom and front perspective view;

FIG. 3 is a front elevational view;

FIG. 4 is a rear elevational view;

FIG. 5 is a bottom and front perspective view, shown with elements thereof estranged and in bracket; and,

FIG. 6 is a front elevational view thereof.

The broken line showing of a strap is for illustrative

purposes only and forms no part of the claimed design.

FIG. 1

FIG. 2

FIG. 3

FIG. 4

FIG. 5

FIG. 6
